UNITED STATES PATENT OFFICE.

CHARLES F. HELFLINGER, OF HOBART, WASHINGTON.

CONCRETE SHINGLE.

Application filed August 17, 1925. Serial No. 50,777.

To all whom it may concern:

Be it known that I, CHARLES F. HELFLINGER, a citizen of the United States, residing at Hobart, in the county of King and State of Washington, have invented certain new and useful Improvements in Concrete Shingles.

My invention relates to improvements in shingles, and it consists in the combinations, 10 constructions and arrangements herein described and claimed.

An object of the invention is the provision of a novel shingle which has means whereby it can be secured firmly in place 15 in association with other like shingles to produce a fire-proof and leak proof roof covering which will lie close to the sheeting boards on which the roof covering is disposed.

20 A further object of the invention is the provision of a shingle of the character described which is practically impervious to the weather and which need not have any openings therethrough such as ordinarily 25 are necessary for the passage of nails which are used to secure shingles provided prior to the invention in place.

Other objects and advantages of the invention will be apparent from the following 30 description, considered in conjunction with the accompanying drawings, in which

Figure 1 is a plan view of a fragmentary portion of a roof covering formed of shingles embodying the invention.

35 Figure 2 is a section along the line 2—2 of Figure 1.

Figure 3 is a perspective view of one of the improved shingles.

40 Figure 4 is a fragmentary longitudinal sectional view of the upper end portion of one of the shingles, showing an attaching tab partially embedded in the upper end portion of the shingles.

45 Figure 5 is a perspective skeletonized view, showing the reinforcing means of the improved shingle, and

Figure 6 is a longitudinal vertical section 50 through the shingle, the attaching tab for the upper end of the shingle being omitted,

55 Figure 7 is a fragmentary plan view of a portion of roof covering formed of shingles embodying the invention and having exposed portions of slightly different outline

than that of the shingles shown in the preceding views, 55

Figure 8 is a relatively reduced perspective view of still another form of shingle embodying the invention.

The improved shingle comprises a body 1 made of concrete or other suitable incombustible material. The body 1 increases uniformly in thickness from its upper end to its lower end and may have an desirable configuration.

A metallic attaching tab comprises a corrugated portion 2 which is imbedded in the body of the shingle midway between the side edges of the shingle body at the upper end of the latter when the shingle is formed and an extending portion 3 which extends beyond the upper end of the shingle body and may be provided with an opening 4 for a purpose to be presently stated.

The side edges of the shingle body preferably are straight and parallel. The upper edge of the shingle preferably extends at right angles to the direction of length of the side edges of the shingle body. The lower edge of the shingle body may have any desirable configuration and may curve concavely at 5 for equal distances from the opposite ends thereof and then extend at 6 at right angles to the direction of length of the side edges of the shingle body, thus producing

a prolongation or extending portion 7 85 at the lower end of the shingle midway of the width of the latter, as best seen in Figures 1, 3 and 5, the lower edge of the shingle body may have beveled corner portions as indicated at 5^a in Figure 7, or may extend at right angles to the side edges of the shingle body as indicated at 5^b in Figure 8 or at any other angle to the direction of length of the shingle body.

The shingle body is provided with a right angular locking or fastening strip comprising an arm 8 which is embedded in the shingle body midway of the width of the shingle and somewhat nearer to the lower end of the shingle body than to the upper end thereof. The right angular fastening member also includes a transversely corrugated arm or engaging portion 10 which extends from the body of the shingle substantially at right angles to the lower face 100 of the latter.

The shingle body also is formed with shingles of adjacent courses are staggered opposite notches 11 in the side edges thereof. These notches extend obliquely between the lower and upper faces of the shingle body 5 so that the upper ends of the notches are slightly nearer to the upper end of the shingle body than the lower ends of said notches. The notches 11 are located in the side edges of the shingle body in the plane 10 which is somewhat nearer to the lower end of the shingle than to the upper end of the shingle but farther from the lower end of the shingle than the fastening member 8-10.

The shingle body is reenforced by a wire 15 frame which is imbedded in the material of which the shingle body is formed midway between the top and bottom faces of the shingle body. This wire frame may comprise longitudinal members 12 which extend 20 in the shingle body near its side edges, transverse members 13 and 13^a, respectively which extend in the shingle body near the ends thereof, and diagonal members 14 and 15, respectively, each of which extends between 25 opposite corners of the reenforcing wire frame. One of the diagonal reenforcing members, as 14 may be twisted around the other diagonal reenforcing member at the center of the reenforcing wire frame, as at 30 16.

From the foregoing description of the various parts of the device, the operation thereof may be readily understood.

A plurality of the improved shingles may 35 be used to form a roof covering, a side covering for a frame structure, or for like use. When used to produce a roof covering, the shingles are laid in courses as shown in Figs. 1 and 2. The course of shingles 1 40 nearest an eave of the roof are laid in position to overlap a course of eaves or starting shingles 17 which may differ from the shingles 1 only in that the former do have the prolongations 7, the slots 11, and the 45 fastening member 8-10 of the latter. The fastening members 8-10 of the first course of shingles 1 therefore may be omitted and the portions of the eaves shingles 17 and of the shingles 1 of the first course which are 50 exposed to the weather are secured to the roof sheeting 18 by nails 19 which are driven through preformed openings in the shingles 1 of the first course and through the eaves shingles, cement mortar being used to seal 55 the upper ends of the openings in the shingles in which the nails 19 are partially received and to cover the upper ends of the nails.

The attaching tab 3 at the upper end of 60 each shingle is secured to the roof sheeting by nails 20 which are driven through the openings 4 into the roof sheeting. The notches 11 of adjacent shingles in the same course register with each other and are 65 filled with concrete mortar, as at 21. The

shingles of adjacent courses are staggered and the depending portion 10 of each shingle 1 of the courses above the first course of shingles 1 is projected into the concrete mortar in the notches 11 between the two 70 adjacent shingles 1 of the next lower course before the concrete mortar hardens and the shingles 1 then is pressed down flatwise onto the overlapped portion of the adjacent shingles of the next lower course, whereby 75 the shingles will be secured closely and firmly to one another and to the roof sheeting and a leak proof and fire proof roof covering thus will be produced. The feature of having the shingles 1 increasing in 80 thickness toward its lower end assures a relatively thick roof covering when a given number of shingles are used to cover a roof sheeting of a given area 1.

Obviously, the invention is susceptible to 85 embodiment in forms other than that which is illustrated in the accompanying drawings and I therefore consider as my own all such modifications and adaptations thereof as fairly fall within the scope of the ap- 90 pended claims.

I claim:

1. A shingle having a body formed of concrete, longitudinal reenforcing wire members embedded in said body adjacent to the side edges of the body, transverse-re- 95 enforcing wire members embedded in the body adjacent to ends of the body and joined to the ends of the longitudinal re- enforcing members, and diagonal reenforcing members extending in said body and joined to said longitudinal and transverse wire members.

2. A shingle having transversely alined notches in the side edges thereof and an 105 attaching member secured to the under face of the shingle midway between the side edges of the shingle and depending sub- stantially at right angles to the lower face of the shingle, as and for the purposes 110 described.

3. A shingle having transversely alined notches in the side edges thereof substan- 115 tially intermediate the length of the shingle, said notches extending obliquely between the upper and lower faces of the shingle, and an attaching member secured to the shingle and depending at right angles thereto to midway of the width of the shingle and between the transverse median line and the 120 lower end of the shingle.

4. A shingle having transversely alined notches in the side edges thereof substan- 125 tially intermediate the length of the shingle, said notches extending obliquely between the upper and lower faces of the shingle, an attaching member secured to the shingle and depending at right angles thereto mid- way of the width of the shingle and between the transverse median line and the lower 130

- end of the shingle and a flat attaching member secured to the upper edge portion of the shingle intermediate the width of the latter and extending beyond the upper end of the shingle, said last named attaching member being apertured.
5. A shingle having transversely alined notches in the side edges thereof substantially intermediate the length of the shingle, 10 said notches extending obliquely between the upper and lower faces of the shingle, and an attaching member partially embedded in the shingle and depending at right angles thereto midway of the width 15 of the shingle and between the transverse median line and the lower end of the shingle, said attaching member being transversely corrugated.
6. A shingle having a body formed of 20 concrete, said body having opposite lateral notches, a right angular fastening member, means embedded in the concrete body of the shingle for securing one arm of said right angular fastening member flatwise 25 against the under face of said shingle body, and a second attaching strip having a corrugated portion embedded in the upper edge
- portion of said body and having an extending portion at the upper end of the shingle midway of the width of the latter. 30
7. In a roof covering, lapped courses of shingles, the shingles of adjacent courses being staggered, each of said shingles having notches in its side edges intermediate the length of the shingle and having a pendant attaching arm secured to the under face thereof midway of the width of the shingle and between the transverse median line and the lower end of the shingle, said pendant attaching arm projecting into the registering notches in the adjacent edges of adjacent shingles in the next lower course, a cementitious substance filling the space between said pendant attaching arm and the walls of said registering notches and preventing displacement of said pendant arm from position in said registering notches, attaching tabs secured to the upper edge portion of each of said shingles and extending above said shingle, and a nail driven 40 through said last attaching tab for securing the upper end portion of said shingle flatwise to the roof sheeting. 45

CHARLES F. HELFLINGER.
